UNITED STATES PATENT OFFICE.

FLORENT PHILIPPE, SR., OF SOUTH CHARLESTON, WEST VIRGINIA.

TOWEL HANGER.

Application filed November 22, 1923. Serial No. 676,281.

To all whom it may concern:

Be it known that I, FLORENT PHILIPPE, Sr., a citizen of Belgium, and a resident of South Charleston, in the county of Kanawha 5 and State of West Virginia, have invented a new and Improved Towel Hanger, of which the following is a description.

My invention relates to a towel hanger and particularly to a hanger comprising 10 spring-pressed jaws to grip the towel, said towel adapted to be separated by the pressure of the finger in the placing of the towel between the jaws.

The general object of my invention is 15 to provide a towel hanger of the indicated class improved in various particulars with a view to promote strength with simplicity and to provide a construction in which the parts may be produced cheaply and assembled with facility.

A more specific object of the invention is 20 to provide a construction permitting the ready dismounting of the jaws and the disassembling of the device when required for repair or otherwise.

The manner and means whereby the above and other objects are attained will clearly appear as the description proceeds.

Reference is to be had to the accompanying 25 drawings forming a part of this specification, it being understood that the drawings are merely illustrative of examples of the invention.

Figure 1 is a front elevation of a towel 30 hanger embodying my invention indicating the same clamping a towel a fragment of which is conventionally shown;

Figure 2 is a side elevation;

Figure 3 is a plan view of the blank from 35 which the back and jaw supports are formed;

Figure 4 is a front elevation of another form of my improved towel hanger;

Figure 5 is a plan view of the hanger 40 illustrated in Figure 4;

Figure 6 is a front elevation of my towel hanger modified slightly over the form shown in Figure 4.

In carrying out my invention in accordance with the example illustrated in Figures 1 to 3, a back plate 10 is provided formed from blank 110, Figure 3. The lower end 11 of the back plate 10 is directed forwardly and in compound curved form so that the terminal edge is deflected downwardly on curved lines. At the sides of

the back plate 10 at the top, forwardly directed side wings 12 are produced integral with said back plate, said wings being formed of members bent up from the blank 40 110, the wings being indicated in the blank, Figure 3, by the numeral 112. The plate has holes 13 to receive screws or other fastening means for securing the back plate to a wall or other support. Each wing is 45 formed at its lower edge with a laterally deflected lug 14 in which a hole 15 is formed.

Retractile springs 16 have their lower hooked ends 17 passed through said holes 15 of the lugs 14. The upper hooked ends 70 18 of the springs 16 are passed through holes 19 in upper ends 20 of the clamp jaws 21, the lower ends 22 of which diverge on curved lines.

The upper ends 20 of the jaws 21 are disposed at right angles or approximately so to the bodies of the jaws and said jaws are held by the springs 16 in convergent relation. The wings 12 form supports on which the jaws 21 may freely rock. The arrangement described causes the jaws to come together at the medial line of the hanger. 75

With the described construction the towel is taken hold of at one corner between the thumb and second finger leaving the corner 80 projecting above the top of the forefinger. The forefinger is employed to force the towel down with a sudden movement between the convergent jaws 21, the pressure serving to spread said jaws against the 85 tension of springs 16. The downward pressure by the forefinger is continued until the finger passes through the jaws and is arrested by stop member 11, the corner portion of the towel which extends above the 90 forefinger remaining between the jaws to be gripped thereby when the jaws close in response to the reaction of springs 16, thereby leaving the towel suspended by its corner as indicated in Figures 1 and 2. 100

To remove the jaws 21 when occasion arises to do so, it is only necessary to press one jaw toward the adjacent wing 12 a sufficient distance to permit the other jaw 21 to be swung upwardly and lifted from the supporting wing 12.

In Figures 4 and 5 a single clamp jaw is employed in connection with a fixed coacting element. The single jaw 121 has an angular terminal 120 acted upon by a spring 116 110 as in the first-described construction. The back plate 210 has a wing 212 on which the

jaw 121 may rock and it has a fixed wing 221 toward which the jaw 121 is pressed by the spring 116. Since the single jaw 121 is oblique to the fixed wing 221 I preferably provide on said wing 221 an upper terminal 5 directed upwardly and laterally outward to guide the towel between said wing 221 and the jaw 121.

In the form shown in Figure 6 a single 10 jaw 321 is employed and the arrangement is precisely the same as in Figure 4 except that in Figure 6 the fixed wing 421 with which the movable jaw 321 coacts is at the right hand side of the back plate 310 instead of 15 at the left side as in Figure 4. The same spring 116 and members 120 and 26 are employed in Figure 6 as in Figure 4. Thus, it will be seen that the several constructions have in common a clamp jaw and an element 20 coacting with said jaw to clamp the towel; the coacting element in Figures 1 and 2 is the second movable jaw whereas in Figures 4 and 6 the element coacting with the 25 jaw is the wing 221 or 421.

I would state in conclusion that while the 30 illustrated examples constitute practical embodiments of my invention, I do not limit myself strictly to the exact details herein illustrated, since, manifestly, the same can 35 be considerably varied without departure from the spirit of the invention as defined in the appended claims.

Having thus described my invention, I 35 claim:

1. As a new article of manufacture, a 40 towel hanger comprising a supporting ele- 45

ment, a spring-pressed clamp jaw, said element having a member on the upper edge of which said jaw freely rests and is rockably supported, and an element coacting with 40 said jaw and between which and the jaw the towel is adapted to be clamped.

2. As a new article of manufacture, a 45 towel hanger comprising a back plate, a wing rigid thereon, a jaw seated and resting on the top edge of said wing and free to rock thereon, and an element between which and the said jaw the towel is adapted to be clamped.

3. As a new article of manufacture, a 50 towel hanger comprising a back plate, a forwardly directed member on said back plate, a jaw rockably mounted on the upper edge of said member, and a forwardly directed member rigid on the back plate at 55 the side opposite the first-mentioned member and constituting an element coacting with said jaw to clamp the towel.

4. As a new article of manufacture, a 60 towel hanger comprising a back plate, a forwardly directed member on said back plate, a jaw rockably mounted on the upper edge of said member, and a member rigid on the back plate at the side opposite the first-mentioned member and constituting an element 65 coacting with said jaw to clamp the towel, said second-mentioned member having the upper end thereof directed upwardly and laterally outward to guide the towel into position to be clamped.

FLORENT PHILIPPE, SR.
